RACE GAME

José Co Callol, Arequipa, Peru

Application February 10, 1933, Serial No. 656,083

2 Claims. (Cl. 273—86)

This invention relates to an improved race game and more particularly to apparatus of the known type comprising a reciprocating or vibrating track upon which model horses or other objects are caused to travel in one direction due to the manner in which the track is caused to move quickly in one direction and relatively slowly in the opposite direction. In such apparatus as heretofore proposed, manually operated mechanism and electrically operated motors have been employed for imparting rotary motion to members from which reciprocating or vibrating motion in one direction is imparted to the track which latter is moved in the other direction by spring means.

One object of the present invention is to provide an apparatus of this type of simplified and improved construction and which will be efficient in its operation and can be cheaply manufactured.

A further object of my invention is to provide a race game playing apparatus comprising a track of the type described having actuating means operated electromagnetically so that the actuating mechanism is of extreme cheapness and simplicity and is very light, strong and durable. A still further object of my invention is to provide the electro-magnetic operating means with a suitable control whereby the speed of operation and consequently the rate of travel of the horses or other objects may be conveniently controlled. Still another object of my invention is to provide an apparatus of this type which is particularly adapted for use on board ship and is adapted to swing about a longitudinal axis so that the track does not tilt to one side or the other due to the movement of the deck on which it is mounted.

With these and other objects in view, the invention consists in the novel construction and arrangement of parts hereinafter described, illustrated in the accompanying drawings and particularly pointed out in the appended claims, it being understood that various changes in the form, proportions, size and minor details may be made without departing from the spirit of the invention or sacrificing any of the advantages thereof.

In the drawings, Fig. 1 is a perspective view showing one form of the apparatus; Fig. 2 is a vertical longitudinal section thereof taken on the line 2—2 Fig. 1; Fig. 3 is a view of part of the apparatus taken on the line 3—3, Fig. 2; Fig. 4 is an enlarged cross section taken on the line 4—4; Fig. 3; and Fig. 5 is a similarly enlarged vertical section taken on the line 5—5, Fig. 4, and also showing a wiring diagram.

In the form shown on the drawings an open underframe 10 is formed with cross bars 11 having inwardly projecting studs 12 mounted in open channels or holes provided at the upper ends of the uprights 13 which latter are supported upon vertically adjustable feet or base supports 14 in such manner that the frame 10 is free to swing on a longitudinal axis passing through the said studs 12 while a balance weight 15 is hung well below the said axis and is carried on a longitudinal rod 16 connected with the frame 10 by depending rods 17 so that the frame 10 is prevented from tilting sidewise when the deck 18 is in a sloping position.

Mounted on the frame 10 is a movable track 19 which is preferably formed of thin sheet metal or other convenient substantially rigid material and depending from the underside of the track 19 are two brackets 20 adapted to serve as stops for the track when engaged by the said cross-bars 11 of the frame 10, so as to limit the longitudinal movement of the track upon the frame, and the left hand stop bracket 20, Fig. 2, is normally retained in engagement with its cross-bar 11 by means of a spring 21 connected at one end to a hook 22 on the underside of the track and connected at its opposite end to an eye carried on a slide piece 23 which latter is mounted on guide rods 24 on the end of the frame 10 and an adjusting screw 25 is provided for moving the slide 23 upon the rod 24 in order to vary the tension of the spring 21. Between the track 19 and the frame 10 ball-bearings 26 are provided, these balls being interposed between grooved blocks 27 on the underside of the track, and similarly grooved blocks 28 on the upper surface of the frame 10, so that the track may move smoothly in a longitudinal direction in the manner herein-after described.

Mounted on the frame 10 is an electro-magnet 29 which cooperates with a plate 30, Figs. 2 and 3, so that when the electro-magnet is energized, the plate 30 is drawn towards the left and when the magnet is deenergized the plate 30 moves to the right under the action of compression springs 31 provided on rods 32 secured to the back of the plate 30 and passing through openings in cross-bars 33 on the frame 10. The springs 31 are mounted under tension between weights 34 (secured on the rods 32) and the face of one of the cross-bars 33.

The electro-magnet 29 also cooperates with a swinging plate 35 mounted on a spindle 36 and adapted to swing in a clockwise direction—Fig. 5—into engagement with the magnet when the

110

latter is energized and adapted to be moved away from the magnet by means of a weight 37 adjustably mounted on an arm 38 when the magnet is deenergized. The arm 38 extends through a saddle piece 39 and is engaged by an adjusting screw 40, by means of which the relative position of the arm 38 and the piece 39 may be finely adjusted. The magnet is carried on cross-bars 41 secured to the frame 10, and depending from one of the cross-bars 41 is a strap 42 to which is secured a bracket 43 carrying a contact device comprising a carbon block 44 normally engaged by a contact stud 45, which is pressed into contact with the block 44 by means of a spring 46, the arrangement being such that when current is supplied to the electro-magnet, the plate 35 is drawn thereto thus raising the arm 38 and consequently the stud 45 which is secured to the saddle piece 39 thereby breaking the circuit and causing deenergization of the magnet which results in downward movement of the stud 45 under the action of the spring 46 thus making and breaking the circuit and consequently vibrating the plate 30, which latter engages a depending bracket 47 on the underside of the track 19 so that the latter is caused to vibrate, and the arrangement is such that the movement of the track 19 towards the right is relatively fast while the movement towards the left is relatively slow so that the horses or other objects 48 are caused to move towards the left over the surface of the track, and this surface is preferably provided with protuberances 49 for the purpose of deflecting or retarding the horses 48 to add to the uncertainty of the game.

The electrical diagram shown at Fig. 5 comprises a connection 49 from the stud 45 to a control switch 50, a line 51 from the switch 50 to the source of power 52, a line 53 from the source of power to one pole of the electro-magnet 29 and a line 54 from the other pole of the magnet to a rheostat 55 and a line 56 from the rheostat to a plate 57 in contact with the said block 44 so that movement of the stud 45 relative to the said block 44 makes and breaks the circuit. The operation of the track is controlled by the main switch 50 while the rheostat 55 may be utilized to vary the speed of travel of the horses or other objects along the track. This apparatus is adapted for use on board ship, at amusement resorts and in

the home and elsewhere. The model mounted in the manner shown particularly at Figs. 1 and 2 is intended for use on board ship, and smaller, cheaper and more portable forms of the apparatus may be provided without self-levelling means for use in the private home. 80

Although the drawings and the above specification disclose the best mode in which I have contemplated embodying my invention, I desire to be in no way limited to the details of this disclosure, for in the further practical application of my invention, many changes in form and constructions may be made as circumstances require or experience suggests without departing from the spirit of the invention within the scope of the appended claims. 85 90

What I claim is:

1. In a race game apparatus having a support, a frame mounted on said support, a racing surface slidably mounted on said frame, tension means for drawing the racing surface in one longitudinal direction, and electromagnetic means for drawing the surface in the opposite direction against the action of said tension means, said electromagnetic means including a pivoted element adapted to swing upon energization of said electromagnetic means, and means raised by the swinging of said element for automatically controlling the de-energization of said electromagnetic means. 95 100 105

2. In a race game apparatus having a support, a frame mounted on said support, a racing surface slidably mounted on said frame, tension means for drawing the racing surface in one longitudinal direction, and electromagnetic means for drawing the surface in the opposite direction against the action of said tension means, said electromagnetic means including a pivoted plate adapted to be swung into a vertical position by the electromagnet of said electromagnetic means, a weighted arm secured to said plate for swinging said plate away from the electromagnet of said electromagnetic means when the latter is de-energized, and contact means controlled by the movement of said weighted arm for controlling the energization of the electromagnet of said electromagnetic means. 110 115 120 125
